CLASSIFICATION SYSTEM FOR SHEET SORTING

Walter N. Lundahl, Hopkins, Minn., assignor to Westinghouse Electric Corporation, East Pittsburgh, Pa., a corporation of Pennsylvania

Application July 22, 1950, Serial No. 175,322

18 Claims. (Cl. 164—68)

The present invention relates, in general, to a classification system for sheet material, and, more particularly, to an automatic classifying system for controlling the ejection of defective sheet steel from handling apparatus.

In accordance with the prior art of which I am aware the sorting and classification of sheet material, especially cold rolled steel and tinned steel involves a tremendous waste due to the ejection of undefective material with the actually defective material. Sheet material passing through a flying shear, such as in a steel mill, moves very rapidly, and in the operation of some prior art apparatus the sheet preceding and the sheet following the defective sheet are frequently ejected with it. Mechanical synchronization systems are not sufficiently precise to throw-out only the defective material sheet and to transmit the sound sheets. The components of such system cannot be accelerated at a sufficiently high rate to accomplish this object. An electric control system to sort good sheets from defective sheets is shown in Dowell Patent 2,433,685, especially in Fig. 7.

Accordingly, it is an object of my invention to provide a sheet material classifying system which will provide positive ejection of only the defective sheet material while transmitting the undefective sheets.

Another object of my invention is to furnish an automatic sheet material classification system which is improved over those available in the prior art.

A further object of my invention is to provide an automatic classifying system which will avoid the tremendous waste of the prior art systems.

A still further object is to provide an electronic system which can operate with sufficient speed to eject only the defective sheet material while transmitting only the sound sheets.

An additional object of my invention is to provide a classifying apparatus which will not require a reduction in the high flow speed of the sheet material while it removes only the defective material.

A still additional object is to provide a classification system which will eject all of the defective material even when successive sheet lengths are defective.

A further object of my invention is to provide a relatively simple classification apparatus which can be easily maintained and which will have a long operating life.

Another object of my invention is to provide an automatic classification system which can be operated by either a pinhole detector or a thickness gauge indicator.

In general, my invention comprises the provision of a photo-cell counting apparatus (26) to provide an indicating signal after the passage of each sheet material length past a given position, and electronic amplifiers to amplify the output of said photo-cell counting apparatus and feed it to electronic counter circuits. A main counter is provided with a plurality of flip-flop multivibrator stages, one of said stages for each of the sheet material lengths of sheet material between the photo-cell counting apparatus (26) and the quality de-

2

tectors (thickness gauge (12) or pin hole detector (14)). A pinhole detector or a thickness gauge detector or both act as these quality detectors and are located before the shear. They are in turn connected to control the passage of any signals through a first amplifier. A thyratron switch is connected to the output of each stage of the main counter, and controls the operation of one auxiliary counter. One of the latter auxiliary counters is provided for each sheet length between the above mentioned quality detectors and the photo-cell apparatus, and comprises four flip-flop multivibrator stages connected in a similar manner to the stages of the main counter, and, in addition, a switch relay is connected in the output of the fourth stage of each auxiliary counter. The latter switch relays are used to control the operation of a sheet length throw-out mechanism or sorter. A second amplifier is connected between the photo-cell counting apparatus (26) and all of the auxiliary counters.

When a defect in the sheet material approaching the shear is detected by either the pinhole detector or the thickness gauge, a signal is sent to the first amplifier to energize its screen grid circuit. This latter energization allows the counting signal from the photo-cell counting apparatus (26) to pass to the main counter circuit and trigger the stages in the latter counter circuit in response to the movement of the sheet material lengths. As each stage of the main counter is triggered, the negative grid bias on its respective thyratron switch is overcome to fire that thyratron switch. In the output circuit of each thyratron switch the operating winding of a circuit breaker is connected. The output signal from the photo-cell counting apparatus (26), as amplified by the second amplifier, is then fed to the input of respectively one of the auxiliary counter circuits through the now closed circuit breaker as each sheet material length passes the photo-cell detector. The aforesaid circuit breaker is thus connected between the auxiliary counter and the output of the second amplifier to govern the passage of the amplifier photo cell counting apparatus (26). When one of the circuit breakers has been closed to allow the passage of the photo-cell detector counting signal to one of the auxiliary counters, the multivibrator stages of that auxiliary counter are successively triggered thereby to ultimately energize the trip winding on a momentary contact switch. The latter momentary contact switch, one of which is provided for each auxiliary counter, controls the operation of a throw-out mechanism which in turn ejects the defective sheet length. Whichever of the sheet lengths between the pinhole detector and thickness gauge and the photo-cell detector is defective, one of the auxiliary counters will be triggered to accomplish its ejection by means of the said throw-out mechanism. I have chosen for illustration a classification system adapted to operate with four sheet lengths between the photo-cell detector and the pinhole detector or thickness gauge.

The novel features that I consider characteristic of my invention are set forth with particularity in the appended claims. The invention itself, however, both as to its organization and its method of operation, together with additional objects and advantages thereof will best be understood from the following description of specific embodiments when read in connection with the accompanying drawings in which:

Fig. 1 is a circuit diagram of the classification system in which the various components are shown in block diagram form;

Fig. 2 is a schematic circuit arrangement of the classification system with the circuit elements included in each of the block diagrams of Fig. 1 enclosed in dotted line blocks, and;

Fig. 3 is a circuit diagram for an electro-mechanical

classification system in accordance with a modified form of my invention.

In the classification system shown in Fig. 1, a continuous sheet of material 10, such as cold rolled steel or tinned steel sheet, is fed through a thickness gauge detector 12 and a pinhole detector 14 with its associated light source 15 to a flying shear apparatus 16. The flying shear 16 cuts the sheet material 10 into finite lengths 24. A photo-cell counting apparatus 26 with its associated light source 28 is placed the equivalent of four sheet lengths away from the pinhole detector 14 and thickness gauge 12 to detect the passage of the sheared material lengths from the flying shear 16. The output of the photo-cell detector 26 is connected to a main counter 30 through a signal amplifier 32 and a pulse shaper 34. The plate supply voltage of the signal amplifier 32 is controlled through a line connection 36 by the pinhole detector 14 and the thickness gauge 12. A time relay mechanism 38 is placed in the thickness gauge circuit and is synchronized with the speed of the flying shear 16 to allow both the thickness gauge 12 and the pinhole detector 14 to be commonly connected through the same line connection 36 to the signal amplifier 32. The main counter 30 is connected to a plurality of auxiliary counters 40, 42, 44 and 46 respectively through a plurality of thyratron switches 48, 50, 52 and 54 respectively. One of the said auxiliary counters and its corresponding thyratron switch is provided for each equivalent length of sheet material between the pinhole detector 14 and thickness gauge 12 and the photo-cell detector 26.

A second signal amplifier 56 is provided between the photo-cell detector 26 and the auxiliary counters 40, 42, 44 and 46 respectively through a second pulse shaper 58.

The main counter 30 comprises a plurality of multivibrator circuit stages of the usual flip-flop type, one of said multivibrator stages being provided for each auxiliary counter 40, 42, 44 and 46 respectively and equivalent length of sheet material between the pinhole detector 14 or thickness gauge 12 and the photo-cell detector 26. Each of said auxiliary counters comprises four generally similar stages, and the final one of said stages is connected to operate a throw-out mechanism 60. The auxiliary counters are each commonly connected in this manner to the throw-out mechanism control apparatus 60 which governs the operation of a throw-out gate 62 which in turn is thereby placed in the path of the sheet material lengths 24 moving away from the flying shear 16. Throw-out gate 62 may be made of a suitable light material, such as aluminum, to reduce its inertia.

In Figure 2 is shown a more detailed schematic circuit diagram of the classification apparatus generally described above. The photo-cell detector 26 is shown to comprise a triode amplifier 64 having an anode 66, a cathode 68 and a control grid 70. A load resistor 72 is connected between the anode 66 and the positive terminal 74 of a suitable plate voltage supply. A photo-electric cell 76 is connected between the positive terminal 74 of said plate voltage supply and the control grid 70. The control grid 70 is connected to ground through a resistor 78 and a negative grid bias voltage supply battery 80. The anode 66 of the photo-cell detector triode 64 is connected through a coupling capacitor 82 to the control grid 84 of a pentode amplifier tube 86 in the first signal amplifier 32. The anode 88 of the first amplifier pentode 86 is connected through a load resistor 90 to a suitable positive plate voltage supply terminal 91, and on through a pair of paralleled switches 92 and 94 and resistor 96 to the screen grid 98 of the pentode 86. The same screen grid 98 is connected to ground through a condenser 100. The suppresser grid 102 is connected to the cathode 104, which in turn is connected to ground through a cathode resis-

tor 106 and a bias condenser 108. The anode 88 of the pentode 86 is connected to a pulse shaper 34 through a coupling condenser 110.

The anode 66 of the photo-cell detector triode 64 is also connected to the control grid 112 of a pentode tube 114 in the second amplifier 56 through a coupling condenser 116. The same control grid 112 is connected to ground through a grid resistor 118. The anode 120 of this second amplifier pentode 114 is connected to a suitable positive plate voltage supply terminal 122 through a load resistor 124. The screen grid 126 of this same pentode 114 is connected to the same plate voltage supply terminal 122 through resistor 128 and to ground through a grid condenser 130. The cathode 132 is connected to ground through a paralleled cathode resistor 134 and bypass condenser 136. The anode 120 is connected to the second pulse shaper 58 through a coupling condenser 138.

The main counter 30 comprises four stages of multivibrators 140, 141, 143 and 145 respectively, each of which includes a dual triode tube having a first and second cathode 142 and 144, a first and second control grid 146 and 148 and a first and second anode 150 and 152, respectively. The first cathode 142 of each of said dual triodes, is connected to the first pulse shaper 34. The first control grid 146 is connected to its second anode 152 through a paralleled resistor 153 and condenser 155 circuit. The first and second anodes 150 and 152 of each tube are connected to the positive terminal 154 of a suitable plate voltage supply through a load resistor 156. The first cathodes 142 of each tube are commonly connected. The second cathodes 144 of each tube are commonly connected. The second control grid 148 of each tube is connected to the first anode 150 through a paralleled resistor 158 and condenser 160 circuit, and to ground through a grid bias resistor 162. The first and second cathodes 142 and 144 of each tube are respectively connected to ground through a cathode resistor 164. The first control grid 146 of each tube is connected to ground through a grid bias resistor 166.

The second control grid 148 of the first multivibrator stage tube 141 is connected to the second anode 152 of the fourth multivibrator stage tube 140 through a coupling condenser 168. The second control grid 148 of the second stage multivibrator tube 143 is connected to the second anode 152 of the first multivibrator stage tube 141 through a coupling condenser 170. The second control grid 148 of the third multivibrator stage tube 145 is connected to the second anode 152 of the second multivibrator stage tube 143 through a coupling condenser 172. The second control grid 148 of the fourth multivibrator stage tube 140 is connected to the second anode 152 of the third multivibrator stage tube 145 through a coupling condenser 174.

The first anode 150 of the first multivibrator stage tube 141 is connected to the control grid 176 of a thyratron tube 178 in the first control switch 48 through a coupling condenser 180. The first anode 150 of the second multivibrator stage tube 143 is connected to the control grid (not shown in detail) of a second thyratron switch 50 through a coupling condenser 182. The first anode 150 of the third multivibrator stage tube 145 is connected to the control grid (not shown) of a third thyratron switch 52 through a coupling condenser 184. The first anode 150 of the fourth multivibrator tube 140 is connected through a coupling condenser 186 to the control grid (not shown) of a fourth thyratron switch 54.

Each of the thyratron switches 48, 50, 52 and 54 comprises in part a thyratron tube. Respecting the first switch 48, there is provided a thyratron tube 178 having a cathode 188, a control grid 176 and an anode 190. The cathode 188 is connected to ground. The grid 176 is connected to ground through a grid resistor 192 and a negative bias voltage supply battery 194. The anode 190

is connected to a suitable terminal 196 of a positive plate voltage supply through the winding 198 of a circuit breaker 200 and the paralleled contacts 202 and 204 of a momentary contact trip switch 206. The trip switch 206 has an operating winding 208 which is connected to the auxiliary counter 40 for the thyratron switch 48. This winding 208 operates the momentary contact throw-out trip switch 206 which controls the operation of the throw-out mechanism 60. The four thyratron switches 48, 50, 52 and 54 and auxiliary counters 40, 42, 44 and 46 operate in a similar manner respectively.

Each of the auxiliary counters 40, 42, 44 and 46 comprises four multivibrator stages. This is shown in detail for the first auxiliary counter 40 in Fig. 2. Each of its four stages includes a dual triode tube 210, 212, 214 and 216 respectively connected as a multivibrator. Each tube has a first anode 218 and a second anode 220, a first control grid 222 and a second control grid 224 and a first cathode 226 and a second cathode 228. The cathodes 226 and 228 of each tube are connected to ground through respective cathode resistors 230. The first anode 218 is connected to the second control grid 224 of each tube through a paralleled resistor 232 and condenser 234 circuit. The second anode 220 is connected to the first control grid 222 of each tube through a paralleled resistor 236 and condenser 238 circuit. The first control grid 222 and second control grid 224 of each tube are respectively connected to ground through grid resistors 240. The first anode 218 of each tube and second anode 220 of tubes 210, 212 and 214 are respectively connected to the positive terminal 196 of a suitable plate supply voltage through plate load resistors 242. The second anode 220 of the first stage tube 210 is connected to the second control grid 224 of the second stage 212 through a coupling condenser 244. The second anode 220 of the second stage 212 is connected to the second control grid 224 of the third stage 214 through a coupling condenser 246. The second anode 220 of the third stage 214 is connected to the second control grid 224 of the fourth stage 216 through a coupling condenser 248. The second anode 220 of the fourth stage 216 is connected to the second control grid 224 of the first stage 210 through a coupling condenser 250. In the fourth stage 216 the second anode 220 is connected to the positive terminal 196 of a suitable plate voltage supply through the momentary contact trip switch control winding 208. The first cathode 226 of each of the four stages is connected to a pulse shaper 58 and the anode 120 of the second amplifier pentode tube 114 through a coupling condenser 138 and a circuit breaker 200 controlled by the circuit breaker winding 198 in the thyratron 178 plate circuit. Each of the auxiliary counters 40, 42, 44 and 46 is similarly interconnected, and operated by respective thyratron switches 48, 50, 52 and 54, as shown generally in Fig. 1.

In Fig. 3 is shown, instead of the electronic classification system shown in Fig. 1, a modified classification system using electro-mechanical stepping relays substituted for the multivibrator counters previously shown and described above. The thickness gauge detector 12 and pinhole detector 14 are connected to a first electronic amplifier 32 in a similar manner to that shown in Fig. 1. The photo-cell counting apparatus 26 is connected to the first amplifier 32 and second amplifier 56 in a similar manner, also. The output of the first amplifier 32 is connected to control the operation of a master stepping relay 252. Said master stepping relay 252 controls the position of a rotary mechanical switch 254. The output of the second amplifier 56 is fed through the rotating contact 256 of said rotary mechanical switch 254 to one of a plurality of auxiliary stepping relays 258, 260, 262 and 264, dependent upon the position of the rotary contact 256 as determined by the master stepping relay 252. An electrical connection 270 is made between the output of amplifier 56 and each of the auxiliary stepping relays,

5 to allow the pulsing signals from the amplifier 56 to be applied to those auxiliary stepping relays which have been initially triggered through a position of rotational switch 254 or after said switch 254 has been moved to another auxiliary stepping relay position. The outputs of the auxiliary stepping relays 258, 260, 262 and 264 are commonly connected to the throw-out mechanism 60 which controls the throw-out gate 62.

10 The exemplary illustration chosen in Figure 3 shows four auxiliary stepping relays 258, 260, 262 and 264 for operation in a modified four sheet 18, 20, 22 and 24 reject system. Between the pinhole detector 14 and thickness gauge 12 and the photo-cell counter 26 there is a distance equivalent to four sheet lengths as cut by the flying shear 16.

15 The classification system shown in Figure 1 operates as follows. The sheet material 10 to be cut into lengths by the flying shear 16 is first fed through a thickness gauge 12 and a pinhole detector apparatus 14. If the thickness 20 of the sheet material 10 is unsuitable or if pinhole defects are detected by the pinhole detector 14 a signal is fed to the first pentode amplifier 32 through electrical contacts in the plate voltage supply circuit (see Fig. 2) of said amplifier 32. The thickness gauge 12 is connected 25 through a time delay circuit 38 because of the physical displacement between the position of the thickness gauge 12 in detecting the thickness of the sheet material 10 and the position of the pinhole detector 14 in detecting pinhole defects in the sheet material 10. The time delay mechanism 38 is chosen to compensate for the travel time required by the sheet material 10 between the position of the sheet material at the thickness gauge 12 and the position of the sheet material 10 at the pinhole detector 14.

30 35 When either the thickness gauge 12 or the pinhole detector 14 causes the plate voltage supply circuit of the first pentode amplifier 32 to be energized, counting signals from the photo-cell counting apparatus 26 are thereby amplified and passed to the main counter circuit 30 through a pulse shaper 34. The photo-cell counting apparatus 26 gives a counting signal every time a sheet length (such as lengths 18, 20, 22 or 24 shown in Fig. 3 or 24 shown in Fig. 1) passes between it and its light source 28 to allow the light source 28 to energize the photo-cell 26. When the plate voltage is placed across the anode-cathode circuit of the first pentode amplifier 32 by means of either the gauge contact 94 at block 12 or the pinhole detector contact 92 at block 14 (shown in Fig. 2) the pulse output of the pulse shaper 34 and first pentode amplifier 32, corresponding to the output of the photo-cell counting apparatus 26, are used to trigger the multivibrator stages of the main counter 30. As each pulse is fed to the main counter 30 one of the multivibrator stages is successively triggered.

50 55 The output of the photo-cell counting apparatus 26 is fed to the first pentode amplifier 32 and the second pentode amplifier 56. The first pentode amplifier 32 is connected to control the operation of the main counter 30 through a pulse shaper 34, as explained above. The second pentode amplifier 56 is connected to four auxiliary counters 40, 42, 44 and 46 through their respective electronic switches 48, 50, 52 and 54, which are respectively controlled by the four stages 140, 141, 143 and 145 (see Fig. 2) of the main counter 30.

60 65 When a defect or unsuitable sheet thickness is detected by either the thickness gauge 12 or the pinhole detector 14, the plate-cathode circuit of the first pentode amplifier 32 is energized. This allows the pulse output of the pulse shaper 34, corresponding to the counting signals from the photo-cell counting apparatus 26, to trigger the respective multivibrator stages of the main counter 30. As each multivibrator stage 140, 141, 143 or 145 (see Fig. 2) of the main counter 30 is triggered, it causes its respective thyratron switch 48, 50, 52 or 54 to fire. When 70 75 a thyratron switch 48, 50, 52 or 54 fires, it allows the

output of the second pulse shaper 58 through from the second pentode amplifier 56, corresponding to the output signals of the photo-detector 26, to pass to its respective auxiliary counter. When one of the auxiliary counters receives this pulse, its multivibrator stages are triggered in a manner well known to those skilled in the art to energize the trip winding 208 (see Fig. 2) of a momentary contact throw-out trip switch 206 (see Fig. 2). The latter switch 206 energizes the throw-out mechanism 60 of a throw-out gate 62 which in turn rejects the defective sheet lengths.

In Figure 2 is shown a more detailed schematic circuit of the apparatus shown in Figure 1 and above described. When either the thickness gauge 12 or the pinhole detector 14 are energized due to an unsuitable sheet thickness or pinhole defect, the screen grid circuit of the first pentode amplifier 32 is energized to allow the counting pulses from the photo-cell 76 due to the passage of sheet lengths and which are amplified in the triode amplifier 64, to pass through the first pentode amplifier 32. The output signals of the first pentode amplifier 32 pass through a pulse shaper 34 to the first anode-first cathode circuit of each multivibrator stage 140, 141, 143 and 145 of the main counter 30.

Under normal operation, when the sheet material 10 is satisfactory in thickness and free from pinhole defects, the screen grid circuit of the first pentode amplifier 32 is not energized, and the first half (150—142) of the first multivibrator stage 141, the second 143 and third 145, and the second half (152—144) of the fourth 140 multivibrator stages of the main counter 30 are conducting. When pulses are fed through the first pulse shaper 34 to the first anode-first cathode circuit of each multivibrator stage 140, 141, 143 and 145, the first half of the fourth stage 140 is triggered due to the reduction of its cathode potential by the triggering pulse. When the first half of this fourth stage 140 is conducting, its first anode 150 potential is thereby reduced to lower the second control grid 148 potential of the second half of this same stage 140 to interrupt the conduction of said second half. When the second half of the fourth stage 140 stops conducting, the potential of its anode 152 rises, which in turn increases the potential of the second control grid 148 of the first stage 141. This causes the second half of the first stage 141 to start conducting to lower the potential of its second anode 152. This second anode 152 lowered potential is reflected to the first control grid 146 of the first stage 141 to terminate the conduction of the first half.

When the first half of the first stage 141 stops conducting, the potential of its anode 150 is increased, which in turn reflects an increased potential on the control grid 176 of the thyatron switch 48 for the first auxiliary counter 40. When the control grid 176 for the first thyatron switch 48 has this increased potential, it causes the thyatron 178 to fire to energize the circuit breaker winding 198 for the first auxiliary counter 40. When this circuit breaker winding 198 is energized, the circuit breaker contact 200 is closed to allow counting pulses from the second pulse shaper 58 corresponding to the output of the photo-cell detector 26, through from the second pentode amplifier 56 to the first auxiliary counter 40 first cathode 226 circuit.

When the screen-grid circuit of the first pentode amplifier 32 is not energized, the first half (218—222) of the first stage 210, the second stage 212, and the third stage 214 of each auxiliary counter are conducting, and the second half (220—228) of the fourth stage 216 is conducting. Relay 208 is supplied with current but since switch 206 is a momentary trip switch it does not affect the separator 62. When a pulse is passed by the first auxiliary counter 40 circuit breaker contact 200, the first cathode 226 of the fourth stage 216 has its potential decreased to start the conduction of the first half of this stage 216. This lowers the potential of the first anode

218 of the fourth stage 216 to decrease the potential of the second control grid 224 of the second half of this stage 216 to cause the second half to terminate conduction. Switch 206 is now set for an operation. The non-conduction of the second half increases the second anode 220 potential to correspondingly increase the potential of the second control grid 224 of the first stage 210 to start the conduction of the second half of the latter stage. When the second half of the first stage 210 starts conducting, the potential of the second anode 220 of this stage is decreased to correspondingly decrease the potential of the control grid 222 of the first half of the first stage and drive this half to non-conduction. A second counting pulse through contact 200 will, in the above described manner, trigger the first half of stage 210 to cause its second half to become non-conducting and in turn cause the second half of stage 212 to be triggered. A third counting pulse will cause the second half of the third stage 214 to be triggered. A fourth such pulse will cause the second half of the fourth stage 216 to be triggered. This energizes the throw-out trip switch winding 208 in the second anode-second cathode circuit of the fourth stage 216. Relay winding 208 is energized whenever the second half of stage 216 of the auxiliary counter 40 is conducting. When the first half of this stage 216 is triggered by counting pulses and begins to conduct after the thyatron switch 48 first closes contact 200, the relay winding 208 is deenergized to remove the plate potential temporarily from anode 190 of the thyatron 178. This terminates the conduction of thyatron 178 and resets the thyatron switch circuit for another suitable operation by its operating stage of the main counter 30. However, switch 200 is designed to remain closed long enough to allow the counting pulses from pulse shaper 58 to complete the counting cycle of auxiliary counter 40. At the completion of the counting cycle of auxiliary counter 40, a momentary contact switch operates the throw-out gate 62.

Each of the first 40, second 42, third 44 and fourth 46 auxiliary counters with their corresponding thyatron switches 48, 50, 52 and 54, respectively, operates in a manner similar to that described above with respect to the first auxiliary counter 40.

As a second pulse is fed to the main counter 30 corresponding to the passage of a second sheet length of material relative to the photo-cell detector 26, the now non-conducting first half of the first multivibrator stage 141 is triggered to cause the first half of the second multivibrator stage 143 to stop conducting to fire its corresponding thyatron switch 50 to allow the passage of counting pulses from the second pulse shaper 58 to the second auxiliary counter 43 corresponding to the latter triggered thyatron switch 50.

The operation respecting how many auxiliary counters receive signals depends on the energization of the screen-grid circuit of the first amplifier pentode 32, and thereby how many main counter 30 stages are triggered. If only one sheet length is defective the screen-grid circuit of the first pentode amplifier 32 will be energized only long enough to allow the counting signal from the photo-cell detector 26 to trigger the main counter through but one "flip" to thereby energize thyatron switch 48 and allow counting pulses to be applied to auxiliary counter 40. After the auxiliary counter 40 has completed one complete cycle of operation, the throw-out gate 62 is operated to eject only the defective sheet length. If in addition a second sheet is also defective the screen-grid circuit of the first pentode amplifier 32 is energized for an additional period sufficient to allow a counting signal from the photo-cell detector 26 to energize the second auxiliary counter 42 through a second stage of the main counter 30 and after a complete cycle operate the throw-out gate 62 to eject the second sheet also. If a third and a fourth sheet length are defective, the screen-grid circuit of the first pentode amplifier 32 will be accordingly energized

to eject said third and fourth sheet lengths in a similar manner.

The apparatus of Figure 3 operates in a similar manner basically to the above described apparatus to eject defective sheet lengths, but utilizes mechanical stepping relays 252, 258, 260, 262 and 264 instead of the electronic multivibrator counters 30, 40, 42, 44 and 46, respectively. The screen-grid circuit of the first amplifier 32 is energized in a manner similar to that described with respect to Figures 1 and 2. However, the counting signals from the photo-cell detector 26 operate the master stepping relay 252 to position the rotary mechanical switch contact 256 in one of the four shown positions. With a rotary switch contact 256 position as shown in the diagram of Figure 3, the counting pulses from the photo-cell detector 26 are applied to the first auxiliary stepping relay 258 which would operate to correspondingly cause the ejection of a first sheet length which is defective. If a second sheet length is defective, in addition to and successive respecting the first sheet length, the first auxiliary stepping relay 258 and the second auxiliary stepping relay 260 will be energized by suitable successive positions of the rotary mechanical switch 256. If third and fourth successive sheet lengths are defective in addition to the first and second sheet lengths, the first 258, second 260, third 262 and fourth 264 auxiliary stepping relays will be successively energized through the rotary mechanical switch 256 positions as determined by the master stepping relay 252. As each auxiliary stepping relay is successively operated the throw-out gate 62 through the operation of control mechanism 60 ejects the defective sheet lengths.

While I have shown and described certain specific embodiments of my invention, many modifications thereof are possible. My invention, therefore, is not to be restricted except as is necessitated by the prior art and by the spirit of the appended claims.

I claim as my invention:

1. In apparatus for classifying sheet material including shear means for cutting said sheet material into finite lengths, the combination comprising a photo-cell mechanism responsive to the movement of said finite lengths, an electronic amplifier connected to said photo-cell mechanism, a main stepping relay connected to said amplifier and responsive to the amplified signal from said photo-cell mechanism, a defect detector connected to control the operation of said amplifier, a throw-out mechanism for ejecting defective material lengths, and an auxiliary stepping relay connected between said main stepping relay and said throwout mechanism for controlling the operation of the latter in response to signals from the main stepping relay.

2. In apparatus for classifying sheet material, including shear means for dividing sheet material into a plurality of finite lengths, the combination comprising, a photo-cell mechanism responsive to the passage of said material finite lengths, a first and a second electronic amplifier connected to said photo-cell mechanism, a main electronic counter connected to said first amplifier and having a plurality of stages, one of said stages for each of said material finite lengths between said shear and said photo-cell mechanism, a thyatron switch connected to each of said plurality of stages, a circuit breaker having a winding connected to each of said thyatron switches, an auxiliary counter connected to each of said thyatron switches and connected between said second amplifier and said circuit breaker, a defect detector connected to control the operation of said first amplifier and the passage of signals thereby from said photo-cell mechanism to said main counter, a throw-out mechanism connected to each of said auxiliary counters and adapted to eject defective material in response to the energization of said auxiliary counters.

3. Apparatus for controlling the classifying of material which is subdivided into a plurality of units that are

moved along a predetermined path, including material separating means to separate those units having a predetermined property, comprising, in combination, means for producing a signal in response to said property in said material adapted to be disposed a predetermined distance along said path from said separating means which distance is equal to the space occupied by n units along said path; means including a pickup component adapted to be disposed adjacent said separating means and adapted to be conditioned on reception of one of said signals for counting said units transmitted to said separating means when so conditioned; means actuatable by at least the first counting operation of said counting means for counting said units regardless of whether or not said signals are produced and means actuatable by said last-named counting means when it has passed through n counting operations for operating said separating means.

4. Apparatus according to claim 3 characterized by the fact that the means, including a pick-up component, includes n separate circuits actuatable in succession by successive responses of said pick-up component to said units to initiate separate counting operations of the means for counting said units independently.

5. Apparatus according to claim 3 for the classifying of material which is subdivided into units to separate these units having at least two predetermined properties, a first property and a second property, characterized by first means for producing a first signal in response to said first property and second means for producing a second signal in response to said second property, said first and second means being adapted to be spaced a predetermined distance along the path of the units and being connected to transmit two signals to the means including pick-up means, the connection to said last-named means of the one of said means for producing a signal which is most remote from said separating means including time-delay means for delaying said signal by a time interval corresponding to said spacing.

6. Apparatus for controlling the classification of material moving along a predetermined path, including unitary separating means to separate out portions thereof having either or both of at least two predetermined properties, a first property and a second property, comprising, in combination, a first means for producing a first signal responsive to said first property adapted to be disposed a first predetermined distance along said path from said separating means; a second means for producing a second signal responsive to said second property adapted to be disposed a second predetermined distance along said path from said separating means greater than said first distance; means for actuating said separating means; connections between said first means and said actuating means, and connections including a time delay component for introducing a time delay corresponding to the difference between said predetermined distances.

7. In apparatus for classifying sheet material which is cut into a number of separate units and which passes along a conveyor line while it is being classified, the combination comprising a source of classification signals, sheet material unit counting means to be disposed along said conveyor line a predetermined number of sheet material units spaced from said source of signals, a first control apparatus which is conditioned by said classification signals to respond to said counting means, means responsive to a first of a succession of said predetermined number of said units for actuating said first control apparatus when it is so conditioned, a second control apparatus which is conditioned by said first control apparatus to respond to said counting means, when said first control means is actuated as aforesaid, means responsive to said predetermined number of units for actuating said second control apparatus while it is conditioned as aforesaid, and a sheet material throwout mechanism controlled by said second control apparatus.

8. In sheet material classification apparatus, including

shear means for cutting said sheet material into finite lengths, the combination comprising, a source of classification signals for detecting defective material, a mechanism responsive to the passage of said lengths, a first counter apparatus connected to said mechanism responsive to said lengths item by item for counting the number of said lengths, said counter apparatus being unresponsive to said lengths in the absence of signals from said source, means actuatable by said signal for conditioning said counter apparatus to operate to respond to said lengths, and a second counter apparatus responsive to said lengths item by item actuatable by said first counter apparatus and by said mechanism for controlling the ejection of said defective material.

9. In sheet material classifying apparatus including a mechanism for dividing said sheet material into finite lengths, the combination comprising, a defect detecting apparatus, a first control counter, connections between said detecting apparatus and said counter for conditioning said counter to operate when a defect is detected, means responsive to individual lengths of said material for actuating said counter only while so conditioned, a second control counter, connections between said first counter and said second counter for conditioning said second counter to operate when said first counter is so actuated, means responsive to individual lengths of said material for actuating said second counter only while so conditioned, a material throwout apparatus for ejecting defective lengths, a normally open circuit having switch means therein for closing said circuit for actuating said throwout apparatus when closed, and means responsive to both said counters when they have been actuated a predetermined number of times for closing said switch means.

10. Apparatus for controlling a sheet material classification system including shear means for cutting said material into finite lengths, the combination comprising, a defective material detector, a sheet material length-passage detector responsive to individual lengths of sheet, a first counter circuit, an electronic amplifier connected between said material length passage detector and said first counter circuit, said counter being actuatable by said length detector and said amplifier to count said sheets only when conditioned by the response of said defective-material-detector to defective material, a second counter circuit and a switch apparatus connected to said second counter and to said first counter circuit and responsive to actuation of said first counter for rendering said second counter responsive to said length detector, said second counter when so rendered responsive to said length detector being so responsive regardless of whether or not said defective material detector responds to defective material.

11. Apparatus for controlling sheet material classification apparatus including shearing apparatus for dividing said sheet material into finite lengths, the combination comprising, a defect detector, a mechanism responsive to the movement of said finite lengths, a main electronic counter, an electronic amplifier connected between said mechanism and said main counter for amplifying the output signals of said mechanism, means responsive to said defect detector for conditioning said amplifier to transmit amplified signals to said counter only when said detector detects a defect, an electronic switch connected to said main counter to be actuated thereby, an auxiliary counter, a second electronic amplifier connected between said mechanism and said auxiliary counter for amplifying the output signal of said mechanism, means responsive to said switch when it is actuated for conditioning said second amplifier to transmit signals to said auxiliary counter and classification means responsive to said auxiliary counter.

12. In apparatus for classifying moving sheet material including shear means for cutting said sheet material into a plurality of finite lengths, the combination comprising, a defect detector disposed to respond to defects in said material, a mechanism responsive to the movement of said

finite lengths, a main electronic counter having a plurality of stages, one of said stages for each of a predetermined plurality of material finite lengths, means connected to said detector and responsive to the detecting signals of said detector for conditioning said counter to operate to produce a signal on the detection of a defect in said material, a plurality of thyratron switches connected to said main counter stages, one of said switches for each of said main counter stages, a plurality of auxiliary electronic counters, one of said auxiliary counters connected to each of said switches for operating in response to said signals from respectively one of said main counter stages to count said finite lengths, and a throwout mechanism for ejecting defective sheets connected to each of said auxiliary counters.

13. In classifying apparatus for moving sheet material including shear means for cutting said sheet material into finite lengths, the combination comprising, a mechanism responsive to the movement of said finite lengths and physically located away from said shear means a distance substantially equivalent to an integral number, n , of said finite lengths, an electronic amplifier connected to said mechanism, a main electronic counter connected to said electronic amplifier for responding to the output of said mechanism, said main counter having n different output terminals at which signals appear in succession for successive responses of said counter to said amplifier, a defect detector disposed to respond to defects in said material and connected to said amplifier and adapted to control the operation of said amplifier so that said amplifier causes said counter to produce a response on the detector of a defect, n auxiliary electronic counters, and n thyratron switches, one of said switches respectively connected between each of said auxiliary electronic counters and a corresponding one of the n terminals of said main electronic counter, means for actuating each of said auxiliary electronic counters through the switch to which it is connected in response to a signal on said terminal to which it is connected to count said finite lengths, and a throwout mechanism for ejecting defective sheets connected to each said auxiliary counter.

14. In classifying apparatus for moving sheet material including a shear means for cutting said sheet material into finite lengths, the combination comprising a mechanism responsive to the movement of said finite lengths and adapted to be physically located away from said shear means a distance substantially equivalent to an integral number, n , of said finite lengths, an electronic amplifier connected to said mechanism, a main electronic counter connected to said electronic amplifier for responding to the output of said mechanism, said main counter having n different output terminals at which signals appear in succession on successive responses of said counter to said amplifier, a defect detector disposed to detect defects in said material and connected to said amplifier and adapted to control the operation of said amplifier so that said amplifier causes said counter to produce a response on the detection of a defect, n auxiliary electronic counters, n thyratron switches, one of said switches respectively connected between each of said auxiliary electronic counters and a corresponding one of said terminals of said main electronic counter, means for actuating each of said auxiliary counters to count said finite lengths in response to a signal on said terminal to which it is connected, and a throw-out mechanism for ejecting defective material lengths connected to each of said auxiliary counters.

15. In apparatus for classifying moving sheet material, including shear means for cutting said sheet material into finite lengths, the combination comprising, a photo-cell mechanism for responding to the movement of said finite lengths, a first electronic amplifier connected to said photo-cell mechanism, a second electronic amplifier connected to said photo-cell mechanism, a main electronic counter connected to said first amplifier for responding to the amplified signal from said photo-cell mechanism, a

defect detector disposed to respond to defects in said material and connected to said first amplifier for conditioning it to conduct said signal to said main electronic counter on the occurrence of a defect in said sheet, an auxiliary electronic counter connected to said second amplifier, an electronic switch connected between said auxiliary electronic counter and said second amplifier and operated by said main counter when it responds as aforesaid to condition said auxiliary counter to respond to said second amplifier and count a predetermined number of said finite lengths when so conditioned, and a throwout mechanism for ejecting defective material lengths connected to each auxiliary counter.

16. In apparatus for classifying moving sheet material, including shear means for cutting said sheet material into finite lengths, the combination comprising a photo-cell mechanism for responding to the movement of said finite lengths, a first electronic amplifier connected to said photo-cell mechanism, a second electronic amplifier connected to said photo-cell mechanism, a main electronic counter connected to said first amplifier for responding to the amplified signal from said photo-cell mechanism, a defect detector connected to said first amplifier for conditioning said main counter to conduct said signal to said main electronic counter on the occurrence of a defect in said sheet, an auxiliary electronic counter connected to said second amplifier, an electronic switch operable by said main counter when it responds as aforesaid to condition the operation of said auxiliary electronic counter by said second amplifier and count a predetermined number of said lengths when so conditioned, and a throw-out mechanism connected to said auxiliary electronic counter responsive to its counting of said lengths for ejecting defective material.

17. The apparatus substantially as specified in claim 16, and a momentary contact switch connected between each of said auxiliary counters and said throwout mech-

anism, each said contact switch being actuatable to actuate said throwout mechanism when its associated counter responds to said predetermined number of said lengths.

18. In apparatus for classifying moving sheet material including a conveying line through at least a portion of which said material is transmitted in finite lengths, the combination comprising, a defect detector disposed to respond to defects in said material, a mechanism responsive to the movement of said finite lengths, said mechanism being disposed in said portion of said line a predetermined number of said lengths from said detector, a main electronic counter having a plurality of stages, one of said stages for each of said predetermined number of finite lengths, means connected to said detectors and responsive to said detector for conditioning said main counter to operate on the occurrence of a defect in said material, a plurality of thyratron switches connected to said main counter stages, one of said switches for each of said main counter stages, and a plurality of auxiliary electronic counters, one of said counters connected to each of said switches for operating in response to signals from respectively one of said main counter stages to count said sheet, and a throwout mechanism for ejecting defective material lengths connected to each auxiliary counter.
